D 374 0020

Design for use in lacquer
Plates on Kette 3000
Dated 20 May, 1851.

Ms. 374

P. M. Hutton, Troy, New York

Letters Patent No. 374. Dated May 20, 1851

mm

The schedule referred to in these Letters Patent and making part of the same

mm

To all whom it may concern:

Be it known that I P. M. Hutton of the City of Troy, Rensselaer County, and State of New York have invented or produced a new and original design, ornament or impression to be cast upon cast iron bedsteads; And I do declare that the following is a full and exact description of the same. In the annexed drawing A and B are the head board and foot board, each of which with the legs sustaining it is one piece. C & D are the connecting side pieces, each of which is also one piece.

Des 374

The head board & foot board are alike as are the side pieces. These four pieces are the only ornamental work in the bedstead, and they are ornamented with leaves and curved lines as seen in the drawing. What I claim as my invention & desire to secure by letters Patent is the designs and ornaments upon the parts A. B. C & D. Combined as in the drawing hereto annexed. Dated May 2d, 1850
